[57] CLAIM

The ornamental design for a housing for a control panel mounted instrument, as shown and described.

DESCRIPTION

FIG. 1 is a side perspective view of a housing for a control panel mounted instrument showing my new design.

FIG. 2 is a front perspective view thereof.

FIG. 3 is a rear elevational view thereof.

The left and right sides are identical as are the top and bottom.

FIG. 1

FIG. 3

FIG. 2
